CLAIM

The ornamental design for a packaging carton as shown and described.

DESCRIPTION

1. Packaging carton

1.1 : Perspective

1.2 : Top

1.3 : Front

1.4 : Perspective view in opened condition

1.5 : Perspective view in re-closed position

This design is directed to a packaging carton, which is used for containing adhesive skin patches, for example; Fig. 1.1 is a perspective view, Fig. 1.2 is a top view, Fig. 1.3 is a front view, Fig. 1.4 is a perspective view in opened condition, and Fig. 1.5 is a perspective view in re-closed condition; the broken lines are shown for the purpose of illustrating parts of the article that form no part of the claimed design; the dot-dash broken line indicates a boundary of the claimed design.

1 Claim, 5 Drawing Sheets
